UNITED STATES PATENT OFFICE

2,422,419

NECKTIE

Joseph E. Johnson, Islington, Mass.

Application October 31, 1944, Serial No. 561,281

8 Claims. (Cl. 2—145)

1

This invention relates to a four-in-hand necktie having novel and improved means for fastening its terminal portions to each other and to a shirt button. The invention aims to provide simple and inexpensive fastening means which shall add but little cost of material or labor and which shall modify the necktie as little as possible while still accomplishing its purpose. The invention will be understood by reference to the following description when taken in connection with the accompanying drawing of two embodiments thereof, while its scope will be pointed out more particularly in the appended claims.

In the drawings:

Fig. 1 is a perspective view of a necktie embodying the invention;

Fig. 2 is a sectional view on line 2—2 of Fig. 1;

Fig. 3 is a perspective view of a modification; and

Fig. 4 is a view of a second modification.

Referring to the drawing and to the embodiments of the invention illustrated therein as examples of the invention, there is shown in each embodiment a four-in-hand necktie comprising a band 4 whose central portion is passed around the shirt collar and whose terminal portions 6 and 8, after the formation of the usual knot, overlie each other on the shirt front and cover most of the buttons down the front of the shirt. In the embodiment shown in Fig. 1 the narrower terminal portion of the necktie is abbreviated or shortened as compared with the embodiment shown in Fig. 3 in which the narrower terminal portion is not only longer but wider than the one shown in Fig. 2.

In each embodiment there is attached to the narrower terminal portion 8 a ligature 10 such as heavy thread or cord securely anchored thereto as by stitches 12, and having a free end 14 preferably thickened or reinforced as at 16 as by a series of knots, for example, to give it sufficient substance to facilitate manipulating it in tucking it through or beneath the keepers presently to be described, on the wider terminal portion 6. In the embodiment shown in Fig. 2, this ligature is attached to the narrower terminal portion close to the end of the latter because it is, as stated, abbreviated, while in the case of an embodiment shown in Fig. 3, the ligature 10 is secured to the terminal portion 8 at a considerable distance from the end. In the case of the embodiment shown in Fig. 3, however, the narrower terminal portion 8 is provided with a button-holed eyelet 18 through which the reinforced terminal portion 16 of the ligature 10 may be

passed. Preferably, this eyelet is rather near the anchor 12 of the ligature 10.

The described ligature 10 is intended for attachment to the wider terminal portion 6 and the latter, in each embodiment, is to that end provided with a longitudinal series or succession of keepers 20 beneath or behind which the ligature 10 may be passed as illustrated in Fig. 2. A convenient way of forming these keepers is by the use of a ligature 22 in the nature of a heavy thread or cord having at one end a knot 24, at its other end a knot 26 (see Fig. 2), and between these knots, at intervals, there are stitches 28 which firmly anchor both ends of each keeper 20.

In the case of the embodiment shown in Fig. 2, with its abbreviated narrower terminal portion, in adjusting the tie to the collar and in forming the knot the end of the narrower terminal portion is arranged at a considerable distance above the end of the wider terminal portion as in Fig. 1, for example. This embodiment is desirable because its abbreviated narrower terminal position results in an economy of material as compared with the one shown in Fig. 3, and a further economy results from the lack of the eyelet 18 which characterizes the one shown in Fig. 3. However, some persons would prefer the full length tie shown in Fig. 3.

In the case of each embodiment, the provision of a series of keepers 20 provides a considerable measure of adjustability enabling the ligature 10 to be passed beneath the keeper which is the nearest to the anchor 12 of the ligature 10.

In the case of the embodiment shown in Fig. 1, the ligature 10 is then wound about the thread of the nearest button on the shirt front, thus anchoring both ends of the tie to keep them from becoming disarranged, while in the case of the one shown in Fig. 3, the operation is the same except that the ligature 10 must be passed through the eyelet 18, as shown, before attachment to the button.

In the second modification illustrated in Fig. 4, the construction is the same as in the first form illustrated in Figs. 1 and 2 except that there is employed a ligature 10A, much shorter than the ligature 10, and provided at its free end with a terminal 16A differing from the terminal 16 in that the terminal 16A is in the nature of a small loop of elastic material such as commercially available fabric-covered rubber. This loop should be small enough to require slight elongation to enable it to be passed over a shirt button and thus to fasten the ligature 10A to the button instead

of winding the ligature about the button threads as in the case of the first two forms of the invention.

Having thus described these embodiments of the invention what I claim is:

1. In a four-in-hand necktie, a band having two terminal portions, one of which overlies the other when the necktie is in use, a ligature disposed along one terminal portion and fastened thereto at intervals, thus forming between the fastening points a succession of keepers along the rear face of such terminal portion, and a ligature attached to the other terminal portion and having a free end to be passed under any one of said keepers and then attached to a shirt button.
2. In a four-in-hand necktie, a band having two terminal portions, one of which overlies the other when the necktie is in use, a lengthwise series of keepers facing rearwardly from the rear face of the overlying terminal portion, and a ligature having one end secured to the underlying terminal portion and having a free end to be passed under any one of said keepers to connect said terminal portion together and then attached to a shirt button.
3. In a four-in-hand necktie, a band having two terminal portions, one of which overlies the other when the necktie is in use, a series of keepers along the rear face of one terminal portion, and a ligature having one end secured to the other terminal portion and having a free end to be passed under any one of said keepers and then attached to a shirt button; such other terminal portion having an opening at a considerable distance from its end to receive the free end of said ligature.

4. In a four-in-hand necktie, the combination of a band having two terminal portions, a lengthwise series of keepers along and facing rearwardly from the rear face of one terminal portion, and a ligature secured to the other terminal portion and having a free end to be passed beneath any one of said lengthwise series of keepers and presenting a loop to be looped about a shirt button.

5. In a four-in-hand necktie, a band having two terminal portions, one of which overlies the other

when in use, the underlying one having an aperture, the overlying one being provided with a lengthwise series of keepers, and a ligature secured to the underlying one and having a free end to be passed first under one of said keepers, then through said aperture, and finally secured to a shirt button.

- 10 6. In a four-in-hand necktie, a band having two terminal portions, one of which overlies the other when in use, a lengthwise succession of keepers along the overlying terminal portion, and means carried by the underlying terminal portion to be passed under any one of said lengthwise series of keepers and then secured to a shirt button.
- 15 7. In a four-in-hand necktie, a band having two terminal portions, one of which overlies the other when in use, a lengthwise succession of keepers along and wholly at the rear of the overlying terminal portion, the underlying terminal portion having a part to be passed under any one of said keepers and wholly at the rear of the overlying terminal portion and having an opening to be buttoned upon a shirt button.
- 20 8. In a four-in-hand necktie, a band having two terminal portions, one of which overlies the other when in use, one terminal portion presenting a lengthwise succession of openings wholly at the rear of such terminal portion; and the second terminal portion presenting a part to be passed through one of said openings and wholly at the rear of the first terminal portion and having an opening to receive a button of the shirt.
- 25 30 35
